[57] CLAIM

The ornamental design for a computer controlled time
clock with fold-up keyboard, as shown and described.

DESCRIPTION

FIG. 1 is a left front perspective view of a computer
controlled time clock with fold-up keyboard showing
my new design;

FIG. 2 is a front elevational view thereof;

FIG. 3 is a right side elevational view thereof, the left
side being a mirror image;

FIG. 4 is a top plan view thereof;

FIG. 5 is a bottom plan view thereof;

FIG. 6 is a rear elevational view thereof;

FIG. 7 is a top plan view thereof, with the keyboard in
the unfolded and open position;

FIG. 8 is a right side elevational view thereof, the left
side being a mirror image;

FIG. 9 is a front elevational view thereof, with the
keyboard in the unfolded and open position;

FIG. 10 is a bottom plan view thereof, with the key-
board in the unfolded position and open position;

FIG. 11 is a rear elevational view thereof, with the
keyboard in the unfolded and open position.
